GEORGE W. HEENE, OF CLEVELAND, OHIO

PRINTING MEANS

Application filed May 31, 1928. Serial No. 281,736.

My invention relates to printing means generally and more particularly to printing on balls and to printing type structure.

One of the objects of my invention is to provide a simple, inexpensive, effective, and easily operable means whereby printing can be performed successfully and within the boundaries of the printing characters on compressible material, even or uneven such as 19 golf balls for instance. Another object is to form the character of a type so that the character can be printed easily and in sharp outline on uneven surface. Other objects will appear, or become apparent or obvious 25 or will suggest themselves upon an inspection of the accompanying drawing and in the description of the device shown therein.

In printing, the printing surface of type is inked and brought into contact with the 20 material to be printed upon. When that material is sufficiently hard so that the same does not yield under the printing pressure, the printing can be performed with the usual type but, when this material is compressible 25 under the printing pressure of the type, the ink on the printing surface of the usual type is squeezed out from under the printing surface of the type and is spread out on surface of the material outside of the printing form 30 of the type and thereby does not confine the printing ink within the boundaries of the printing surface on the type and causes imperfect printing as well as blotching of the 35 surface of the material.

In materials with uneven surfaces, such 40 as golf balls for instance, sufficient pressure must be exerted against the surface by the type to depress the high places of the material in order to reach the low places for complete printing. The usual type has a 45 flat or one level printing face and will not print a full letter or character on uneven surface, the ink will be squeezed out from under the type and deposit or spread itself on the surface outside of the boundaries of the letter or character when the surface is of compressible material, and the ink will likewise spread outside of the boundaries of the letter or character and deposit itself further out 50 on the high places of an uneven compressible

surface than on the lower places. In either case, the usual type face will not print a character correctly on either an uneven or compressible surface.

Such type elements as are now commonly 55 used in check protectors and the like, wherein the type elements perforate the paper and ink the edges of the perforations are not desirable because (first) they must perforate 60 surface and (second) do not confine the ink- 65 ing to within the boundaries of the printing face of the type.

My invention distinguishes from the prior 70 art in that the type have means to deposit 75 printing ink on surface printed on within 80 the boundaries of the printing face of the type while a printing operation is being performed on surface of compressible material or uneven material or uneven compressible 85 material and thereby print clear characters 90 on even as well as uneven compressible or uncompressible surfaces.

Although I am aware that various means 95 can be used to attain my object, I have selected one style of apparatus or device and 100 one style of printing type face to illustrate my invention and will describe the same in detail hereinafter, but this illustration and description do not constitute, nor are intended 105 to constitute, a limitation of my invention to the particular matter so shown and described.

In the accompanying drawing mentioned 110 above:—

Fig. 1 is a side view of a ball holding and 115 printing device embodying my invention.

Fig. 2 is an end view of Fig. 1 showing 120 the endwise or sidewise relations of the elements.

Fig. 3 is a plan view of Fig. 1 showing the 125 longitudinal and sidewise relations of elements.

Fig. 4 is a longitudinal section taken in 130 a vertical plane indicated by the line 4—4 135 in Fig. 1 showing interior relations of the 140 elements.

Fig. 5 is a perspective view, on a larger 145 scale, of the printing end of a type having 150 level and depressed portions in the form of serrations on the printing face thereof and 155

a portion of a golf ball adjacent to the printing face.

Fig. 6 is a perspective view similar to Fig. 5 showing level portions as the outline of the character and depressed portions inside of this outline.

Fig. 7 is a section of Fig. 6 taken on the line 7 indicated in Fig. 6 and showing more clearly the structure of the printing face.

Similar reference characters refer to similar parts throughout the views.

The type carrier A rotates with the shaft 10 journaled in the parallel parts 11 of the bar B which has one end thereof hinged to the uprights 12 on the frame C by means of the pin 13 and has the handle 14 in the other end; the portion inward of the handle extends in and is movable up and down in between the uprights 15 on the frame C.

The inking roller D is journaled in the link 16 hinged to the uprights 15 by means of the pin 17 to permit the roller to be brought into and out of contact with the hereinafter described type.

The inking ribbon E extends over the roller 18 journaled in the upper end of the uprights 12 and over the roller 19 journaled in the link 20 hinged to the frame C by means of the pin 21 to permit the ribbon to be brought into or out of contact with the hereinafter described type.

Either the roller D or the ribbon E can be used independently as desired or both can be used conjointly when so desired. Moving means for either the roller or the ribbon, not shown in the drawing, can be provided in any of the forms well known in the art.

The ball F of compressible material and of uneven surface, such as a golf ball, rests in and is rotatable in the socket 22 in the ball holder G on the frame C. Other ball supporting means can be used. The ball can be rotated in the socket by hand or by other means to effect spacing of the printing thereon.

The radius of curvature of the bottom of the socket is shorter than the radius of the ball F so that the same rests on the upper end around the open top of the socket to position the ball laterally or sidewise as well as to support the same vertically for printing thereon.

Variously sized balls can be positioned and supported in this manner by the open top of the socket. Balls diametrically smaller than the one shown will drop down further into the socket while diametrically larger ones will extend further above the socket.

Each of the type members H has a printing character on one end thereof as the letter "A" shown in Fig. 5 for instance and is mounted in the carrier A in such a manner that all of the printing characters face radially outwardly so that any one of the characters can selectively be brought into posi-

tion to print its character on the ball by rotating the carrier until the representation of the selected character is opposite the pointer 23 whereupon the selected character will be on the bottom and in printing position.

In Fig. 5, the printing face 24 of the type members is shown with the letter A as serrated in cross-cut fashion and thereby holds ink in the grooves or pockets 24 A so formed.

In Figs. 6 and 7, the printing face 24 of the type members is shown with the outline 24B of the letter A even or level and depressions 24C between the outline. The ends of the outline 24B can be made sharp to cut material or can be made sufficiently dull so that it will not cut the material as desired or as found necessary or convenient or advantageous for any particular or general material printed upon.

After the ball is in position in the pocket and the carrier is rotated until the representation of the selected character (A in the present instance) is under the pointer, the handle 14 is moved downwardly and thereby moves the carrier and the type downwardly until the face 24 of the selected type contacts the outer surface of the ball. An additional downward pressure on the handle then squeezes some of the material of the higher portions 25 on the surface of the ball out of the way temporarily until the face 24 also contacts the deeper or lower portions 26 whereupon further downward movement of the type is arrested and the ink, deposited on the face 24 by the rotation of the carrier and now confined in or retained in the pockets or grooves or depression, is deposited on the ball surface within the boundaries of the character selected and is not squeezed out beyond these boundaries during the compression of the higher parts of the ball surface.

Due to the resiliency of the material printed on, the ink would be squeezed out beyond the boundaries of the character on the type if the face thereof was smooth or entirely level and flat in the usual type whereas the face in my invention retains or confines the ink to within the boundaries of the face during the printing operation.

The characters on the type are cut deeper than usual to give the material of the ball more space to move into when the type moves such material. The high points of the serrations are generally not sufficiently sharp to cut the material of the ball.

After the printing operation, the letter appears on the surface of the ball in clear and sharp outline or boundaries 27.

I am aware that my invention is applicable to devices and means other than the one shown and described as well as that changes can be made in the structure as well as in the arrangement of elements shown and described within the scope of the appended claims; therefore, without limiting myself

to the precise application of my invention as shown and described nor to the precise structure and arrangement of elements shown and described,

5 5 I claim:—

1. A printing means including a frame, a ball holder positionally fixed thereon and having a socket in the top thereof to position a ball definitely sidewise and to support the same vertically on the upper end thereof, an operating bar hinged to said frame, a shaft journaled in said bar, a type carrier on and rotatable with said shaft, type members carried by said type carrier and moving therewith for upward alinement thereof with said socket and having printing characters thereon of greater length than usual to print the characters thereof in substantially clear outline onto a ball, and printing type inking means having one end thereof positionally fixed on said frame and the other end thereof pivotally supported on said frame and adapted to be moved into and out of inking contact with the type on said type carrier.
2. A printing means including a frame, a ball holder positionally fixed thereon and having a socket in the top thereof to position a ball definitely sidewise and to support the same vertically on the upper end thereof, an operating bar hinged to said frame, a shaft journaled in said bar, a type carrier on and rotatable with said shaft, type members carried by said type carrier and moving therewith for upward alinement thereof with said socket and having printing characters thereon of greater length than usual to print the characters thereof in substantially clear outline onto a ball, printing type inking means having one end thereof fixed in position on said frame and the other end pivoted on said frame and adapted to be moved into and out of inking contact with the type on said type carrier, and indexing means on said shaft to selectively bring any one of said printing types into printing position.

In testimony of the foregoing I affix my signature.

GEORGE W. HEENE.
